UNITED STATES PATENT OFFICE.

SARAH STODDARD, OF OAKLAND, CALIFORNIA.

SEPARATE REMOVABLE QUILT-COVERING.

1,261,314.

Specification of Letters Patent. Patented Apr. 2, 1918.

Application filed September 5, 1917. Serial No. 189,746.

To all whom it may concern:

Be it known that I, SARAH STODDARD, a citizen of the United States, residing at Oakland, in the county of Alameda and State of California, have invented new and useful Improvements in Separate Removable Quilt-Coverings, of which the following is a specification.

This invention relates to a separate removable quilt covering.

One of the objects of the present invention is to provide a separate covering for quilts, which may be quickly applied or removed when either the quilt or covering requires laundering, this being particularly desirable as it not only saves the quilt from being soiled and from being worn by too much laundering, but it also retains it in a more sanitary condition than is otherwise possible. Another object of the invention is to provide a simple means for securing the covering to the quilt and also to provide a covering which permits a rolled edge formation on the quilt, as will hereinafter be described. Further objects will hereinafter appear.

The invention consists of the parts and the construction and combination of parts as hereinafter more fully described and claimed, in which—

Figure 1 is a perspective view of the quilt partly broken away.

Fig. 2 is a cross section of same.

Referring to the drawings in detail, A indicates a standard form of quilt, provided with a permanent cover and filled with cotton padding or other suitable material. Separate from the quilt proper but adapted to be secured thereto is an upper cover section 2 and a lower cover section 3. Said lower cover is considerably larger than the upper cover and the quilt to permit the outer edges to be folded over the top cover.

Both covers are provided with buttonholes arranged at intervals along the edges and crosswise of the quilt, and buttons are attached to the quilt proper to permit the cover sections to be secured thereto. The buttons are sewed directly to the permanent covering of the quilt and as two buttons may be attached in alinement and secured by the same thread, it is obvious that the ordinary tufting employed may be entirely eliminated as the threads securing the buttons will hold the padding in place. The buttons are preferably drawn quite tight when secured, thereby drawing the padding together and simul-

taneously giving an upholstered or heavy padded effect, as the buttons thus secured compress the padding.

In actual practice when applying the outer removable cover, it may be accomplished by first spreading out the quilt on a bed or other flat surface. The top covering may then be spread over the quilt and buttoned thereto. The quilt with the top covering may then be turned over and the bottom cover applied. The quilt is then reversed and the outer edges are rolled over, as shown at 4, and are secured in said rolled position by folding the outer edges of the bottom cover over the roll and buttoning it to the outer rows of buttons. This secures the roll in place and gives an ornamental finish to an ordinary quilt that could hardly otherwise be obtained. This rolling of the quilt is, however, not necessary but as described may be accomplished if desired.

While the description of placing the cover on the quilt proper specifies placing the top cover in position first, it is obvious that either cover may be applied without materially affecting the appearance of the quilt when completed.

The use of two separate removable cover sections is important from several points of view. First of all it can readily be seen that it prevents the quilt proper from being soiled, thereby eliminating the necessity of having it laundered as often as is usually the case. Wear and tear of the quilt proper is eliminated and it is retained in a more sanitary condition. The ornamental appearance of the quilt as a whole is also materially improved as practically any color and pattern of covering may be employed. For instance, the top cover may have one color pattern while the bottom cover may be of a different color. The upturned edges which overlap the top cover will in this manner form a border for the top and thereby materially increase the artistic appearance of the quilt.

The materials and finish of the quilt and the covers applied may be such as the experience and judgment of the manufacturer may dictate and the manner of attaching the covers to the quilt may also be varied. While buttons are here shown, it is obvious that any other suitable means may be employed.

Having thus described my invention, what I claim and desire to secure by Letters Patent is—

1. The combination with a quilt having a

permanent cover, of a separate removable covering therefor, consisting of an upper and a lower section, and means for securing each section to the quilt independently of the other.

- 5 2. The combination with a quilt having a permanent cover, of a separate removable covering therefor consisting of an upper and a lower section, said lower section being 10 larger than the quilt and the upper cover section to permit the edges of the quilt to be rolled and the sides and ends of the lower section to be folded over said roll, and means for securing both cover sections to the quilt.

3. The combination with a quilt having a permanent cover, of a separate, removable covering therefor, said removable covering consisting of an upper and a lower section, and means for securing each section to the quilt.

20

In testimony whereof I have hereunto set my hand in the presence of two subscribing witnesses.

SARAH STODDARD.
